UNITED STATES PATENT OFFICE.

LOUIS STEINBERGER, OF NEW YORK, N. Y.

SYSTEM OF INSULATION.

949,604.

Specification of Letters Patent. Patented Feb. 15, 1910.

Application filed December 4, 1909. Serial No. 531,322.

To all whom it may concern:

Be it known that I, LOUIS STEINBERGER, a citizen of the United States, and a resident of the city of New York, borough of Brooklyn, in the county of Kings and State of New York, have invented a new and Improved System of Insulation, of which the following is a full, clear, and exact description.

My invention relates to systems of insulation for high potential electric conductors to be used in various relations and for various purposes, such as power transmission; and for guy wires or cables employed as stays, towers, or for poles, masts, and other supports used in wireless telegraphy, as well as in ordinary commercial work.

When used in connection with wireless apparatus, my invention tends to prevent leakage and undesirable grounding of the current, either from conductors or from supporting structures for the same.

Generally speaking, my system comprehends a series of insulators, preferably of the thimble type, and a series of other insulators of the rod type, the thimble type insulators being alternated with the rod type insulators, and together therewith comprising a flexible chain of parts which may be extended indefinitely and added to. In this system the various parts may be readily detached and replaced by other parts, and the total number of parts may be increased or diminished at will after the original structure is built, this feature being especially important in instances where, after the installation of a conductor, the voltage is to be increased. By my system provision may be made for increasing the voltage to any desired extent, the various mechanical parts which I employ being of comparatively small size, light weight, and low cost.

My improved system comprehends the employment of a novel structure, including the introduction of springs between the rod type insulators and the thimble type insulators, so that the various parts, considered as a unit, are under spring tension, thereby insuring more or less resiliency whereby the complete structure is relieved in all of its parts, as well as in its entirety, from the effects of sudden and abrupt accidental strains, usually so destructive to mechanism of this kind.

My invention further comprehends pro-

tection for air spaces around certain parts, making up the chain above referred to, the air spaces being so disposed as to insure that at all times the flexible chain of parts, even though completely deluged in rain water, 60 will still afford adequate insulation for all practical purposes.

In addition to the foregoing my invention contemplates various improvements in all the specific kinds of insulators employed in 65 my system.

Among the objects of my invention are the following: I. To protect from the weather a portion of the terminal insulating member, conductor or guy, as the case may be, 70 which may be employed in connection with this system. II. To prevent the line from falling in the event that the insulation of the chain of units or of any part thereof becomes injured or destroyed. III. To give 75 the various parts such conformity as will tend to prevent the creepage of moisture over the various parts, and in doing this will also tend to prevent arcing or puncturing under the influence of currents of high 80 potential. IV. To provide improved forms of units which, when connected together in the form of a flexible chain, as above stated, will admit of the application of additional units for the purpose of increasing the degree of insulation at will. V. To give the 85 various units such conformity as to enable them to be readily connected together and disconnected from each other in order to lengthen or shorten the chain of parts. VI. 90 To give the various parts or units such conformity that the complete chain may be readily extended in various directions—vertically, horizontally, or at any desired angle relatively to the horizon. VII. To so form 95 the units as to admit of their easy and ready handling and assembling without handling parts of heavy weight. VIII. To provide units of such form that, if necessary, they can serve as complete insulators when detached and used alone. IX. To improve 100 generally the construction of the thimble type units and also to improve the construction of the rod type units forming parts of my system.

Although for convenience I show and describe my system as used in connection with thimble type units and rod type units, I do not limit myself thereby, as units of other types suitable for my purpose may obviously 110

be employed without departing from the spirit of my invention.

I do not limit myself to the exact form or precise details of any or all of the parts herein described, nor to the precise number of units disclosed. Neither do I limit myself to any special arrangement of the parts, nor to the use of any prescribed materials. I prefer, however, to employ for most of the insulating parts the material well known in this art as "electrose."

Reference is to be had to the accompanying drawing forming a part of this specification, in which the figure shows a substantially central, vertical section through a structure embodying my improved system.

A number of thimble type insulators are shown at 1, 2 and 3, the insulator 1 being plain at its bottom, the insulator 2 having a skirt 2^a of small diameter, and the insulator 3 being provided with a skirt 3^a of larger diameter. The insulators are provided with thickened portions 4, 5, 6 in which are embedded metallic baskets 7, 8, 9. The basket 7 is provided with an eye 10 which may be connected with another unit or suspended directly from any suitable support. Located within the basket 7 (the lower portion of which has a substantially annular conical form) is a conical head 11 provided with a threaded bolt 12. A cap 13 is threaded and fitted upon this bolt.

A casing 14 is threaded and connected with the cap 13, this casing 14 having generally the form of a cylinder, and loosely extending through its bottom is a rod 15 which is provided at its upper end with a head 16, a spiral spring 17 encircling the rod 15 and engaging the bottom of the casing 14, and also engaging the head 16. When the rod 15 is drawn downwardly, the spring 17 is compressed.

The lower end 16^a of the rod 15 is screw-threaded, and a holder 18 is likewise screw-threaded and is fitted upon the lower end of the rod 15. The holder 18 is provided with a fork 19 through which extends a pivot pin 20. A rod 21 of tough insulating material, such as fiber, has its upper end inserted in the fork 19, the pin 20 passing directly through such upper end. Encircling the rod 21 is a tubular mass 22 of insulating material, preferably "electrose."

The lower end of the rod 21 fits into a holder 23 and is held therein by aid of a pin 24 which extends directly through this fork, this pin being completely enveloped by the lower end of the mass of insulating material 22. The holder 23 is provided with a threaded bolt 25 and fitted upon the latter is a cap 26. A casing 27 is threaded and fitted to the cap 26, this casing having generally the form of a cylinder. A compression spring 28 is mounted within the casing 27 and is engaged by the head 30 of

a rod 29, this rod extending loosely through the bottom of the casing 27 and being provided with a threaded portion 31.

The basket 8 is provided with a threaded portion 32 which engages the threaded portion 31 of the rod 29. Disposed within the basket 8 and spaced therefrom is a substantially conical head 33 which is provided with an eye 34. A tensile spring 35 is provided at its upper end with a hook 36 which engages the eye 34. The spring 35 is provided at its lower end with an enlarged threaded portion 37 which fits into a holder 38, this holder being threaded for this purpose.

The holder 38 is provided with a fork 39 through which extends a pin 40, a rod 41 of fiber, or other tough insulating material extending into the holder 39 and being held thereby aid of the pin 40. A tubular member 42 of "electrose" envelops the rod 41, this tubular member 42, as well as the tubular member 22 of the same material, being corrugated in order to increase the difficulty of leakage and particularly to lessen the creepage of moisture over their surfaces. The lower end of the rod 41 extends diametrically through the upper portion of a holder 43, and through the lower end of the rod 41, extends a pin, 44.

A spiral tensile spring 46 is provided with an enlarged threaded portion 45 which is fitted into the holder 43, the latter being threaded for this purpose. The basket 9 is provided with an eye 47 which is connected with the lower end of the tensile spring 46. Disposed within the basket 9 and spaced therefrom is a substantially conical head 48 provided with a threaded bolt 49. A rod 51 is provided at one of its ends with a sleeve 50 which is threaded internally and fitted upon the threaded bolt 49. The opposite end of the rod 51 is provided with an eye 52. A sleeve 53 of fiber is fitted upon the rod 51, and enveloping this sleeve 53 and the greater portion of the rod 51 is a corrugated tubular member 54 of "electrose". The tubular member 54 is longer than the sleeve 53, so that the ends of the latter are completely enveloped. The tubular member 54 extends into direct engagement with the lower portion of the sleeve 50.

A conductor for high tension currents is shown at 55 and engaging the same is a clamp 56. This clamp is supported by aid of a bolt 57 extending through it and through the eye 52. The rod 51 is well insulated and also well protected from the weather by the sleeve 53 of fiber and the tubular member 54 of "electrose." The rod 51 is, because of its connection with the threaded bolt 49, rigid relatively to the thimble type insulator 3. On this account it cannot, under any swaying motion of the conductor 55, be thrown violently against

the inner edge of the insulator 3, so as to break, or unduly wear, either the thimble type insulator or the coverings for the rod 51. Again, owing to the rigidity of the rod 51, whereby it is held centrally in axial alinement with the thimble type insulator 3, the skirt 3^a of the insulator is located to the best advantage relatively to the rod 51 and its coverings, for the purpose of protecting 10 the same from the weather.

The parts above described and connected as shown constitute my system of insulation. Considering the structure as a whole, it will be noted that it is extensible under mechanical tension, and further that it is flexible to a high degree. Practically any one of the parts, except those which are rigidly embedded in the insulating materials, may be removed and replaced at pleasure. The 15 three hoods shown, with the parts connected with them, and the two rod-like members disposed between the hoods constitute the 20 units which make up the system.

I find it advantageous to employ the units 25 of the rod type in connection with the units of the thimble type, and to arrange them alternately in series. By doing this each rod type insulator is, in a measure at least, protected by the particular thimble immediately over it, and in some instances the rod type unit has additional protection afforded by a skirt of the hood, as, for instance, the hood 2^a. It may happen in some installations that, owing to the peculiarity of such mechanical strains as happen to fall upon the 35 structure, a compression spring is better than a tensile spring. Again, it is desirable that if one of the springs happens to break, the high tension conductor be not thrown 40 to the ground. The springs 17 and 28 are based upon this idea. If either of these two springs should break, the head 16 or 30, as the case may be, could not leave the casing in which it is housed, and consequently the 45 high tension insulator 55 could not be allowed to fall. Such being the case, the compression springs can be made light, thus effecting a saving of weight. It will be noted that the skirts 2^a and 3^a tend to prevent quite a 50 number of parts under them from becoming wet in bad weather, and this not only improves the insulation of the complete structure, but also tends to avoid undue deterioration of the parts thus kept dry. It will 55 also be noted that no matter how severe may be the weather to which my construction is exposed, the parts housed within each thimble are necessarily kept dry. It follows from this that where a large number of insulators of the thimble type are alternated with insulators of the rod type, and the rod type insulators, together with parts associated with them, are suspended within or 60 partially within the thimble type insulators, 65 the rod type insulators and parts associated

with them are maintained wholly or partially dry at all times.

Where my improved construction is used in connection with wireless towers, it may sometimes be desirable to incline the chain 70 of units relatively to the horizon. In this event there are always quite a number of dry surfaces encircling various units and parts of units so that even when rain is falling rapidly the structure, as a whole, affords 75 good insulation.

Having thus described my invention, I claim as new and desire to secure by Letters Patent:

1. A system of insulation, comprising a 80 plurality of thimble type insulators and a plurality of rod type insulators connected together in the form of a continuous chain.

2. A system of insulation, comprising a 85 plurality of thimble type insulators and a plurality of rod type insulators, the thimble type insulators being alternated with the rod type insulators.

3. In a system of insulation, the combination of a plurality of thimble type insulators and rod type insulators, one of said thimble type insulators partially inclosing one of said rod type insulators for the purpose of protecting the latter from the effects of 95 moisture.

4. A system of insulation, comprising a 100 plurality of thimble type insulators, a plurality of rod type insulators, and spring connections between said thimble type insulators and said rod type insulators.

5. A system of insulation, comprising a 105 plurality of insulators, and a spring connection between the same for the purpose of rendering one of said insulators resilient relatively to another.

6. A system of insulation, comprising a 110 thimble type insulator, a rod type insulator extending therewith, and a spring disposed intermediate said thimble type insulator and said rod type insulator.

7. A system of insulation, comprising a 115 plurality of thimble type insulators provided with skirts of different diameters, and a rod type insulator connected with said thimble type insulators and disposed therebetween.

8. A system of insulation, comprising a 120 thimble type insulator, a casing connected therewith and supported thereby, a compression spring disposed within said casing, a rod type insulator, and a member connected with said rod type insulator and engaging said compression spring within said casing.

9. A system of insulation, comprising a 125 thimble type insulator, and a rod type insulator flexibly connected therewith and adapted to move relatively thereto.

10. A system of insulation, comprising a 130 thimble type insulator, a rod type insulator,

- a tensile spring connected with said rod type insulator and with said thimble type insulator, and means for supporting said rod type insulator.
- 5 11. A system of insulation, comprising a thimble type insulator, a rod type insulator extending into said thimble type insulator, and a flexible connection from said rod type insulator to said thimble type insulator.
- 10 12. A system of insulation, comprising a thimble type insulator provided with a thickened portion, a basket embedded within said thickened portion, a head located within said basket and spaced therefrom, a casing supported from said head, a spring mounted within said casing, and a rod type insulator supported by said spring and extending into said thimble type insulator.
- 15 13. A system of insulation, comprising an insulator provided with a portion protected from the weather, and a rod type insulator flexibly connected with said first-mentioned insulator and extending into said portion thus protected.
- 20 14. A system of insulation, comprising a rod type insulator having oppositely disposed ends, holders pivotally connected with said ends, and means for protecting one of said holders from the effects of the weather.
- 25 15. A system of insulation, comprising an insulator provided with a skirt, a casing disposed within said insulator, a spring mount-
- ed within said casing, a rod type insulator, and a pin connected with said rod type insulator and extending into said casing, said pin being provided with a head engaging said spring.
- 30 16. A system of insulation, comprising a plurality of insulators, a tensile spring connecting together two of said insulators, and a compression spring connecting together two of said insulators.
- 35 17. A system of insulation, comprising a thimble type insulator, and a plurality of rod type insulators, said thimble type insulator being disposed intermediate said rod type insulators.
- 40 18. A system of insulation, comprising an insulator provided with a skirt, and a plurality of rod type insulators connected with said first-mentioned insulator and disposed upon opposite sides of the same.
- 45 19. A system of insulation, comprising a thimble type insulator, and a rod flexibly connected with said thimble type insulator and adapted to move relatively to the same.
- 50 In testimony whereof I have signed my name to this specification in the presence of two subscribing witnesses.
- LOUIS STEINBERGER.
